IGNITION SYSTEM FOR FUEL BURNERS

James K. Clark, New Hartford, N. Y., assignor to
The Partlow Corporation, New Hartford, N. Y.

Application May 29, 1939, Serial No. 276,477

5 Claims. (Cl. 158—28)

This invention pertains to ignition systems for fuel burners, and more particularly to electrical control and ignition system for fuel burning furnaces, ovens and the like. The instant application is thus directed to modifications and improvements in the electrical control system for the automatic safety pilot burners shown and claimed in my patent, No. 2,152,790, of April 4, 1939, and therefore has for an object to provide improvements in the equipment disclosed therein.

As in said patent, the equipment includes an electrical system for controlling the fuel supply to pilot and main burners, the electric ignition of the fuel of the pilot burner, and automatic shut-off means for the fuel in the event of fuel failure; the extinguishment of the pilot flame, or failure of the electric current supply.

One of the principal objects of the present invention and improvements over said patent is the provision of means for shutting off the fuel supply to the burners in the event of a short circuit of the high tension ignition means of the electrical control system as might occur by an accumulation of soot in the pilot burner, or a ground of the high tension connection therewith.

Another object of the invention is to improve and simplify the electrical system, as appears in detail in the specification and claims.

Further objects, details, and advantages of the invention will be more fully set forth in the following specification in conjunction with the accompanying drawing which diagrammatically illustrates electrical control means for a pilot and main burner for a furnace or the like in accordance with my invention.

Referring to the diagram, I have shown the electrical control system in accordance with my invention as applied to gas burners for use in furnaces and the like, wherein a main heating burner 1 and a pilot burner 2, are connected to a gas supply main 3, by way of branch conduits 4 and 5 respectively. The gas supply to the main burner is regulated and controlled in the usual manner, a valve 6 in conduit 4 being indicated for the purpose, and similarly a manually operated cut-off valve 7 is shown in conduit 5, for cutting off the gas supply to pilot burner 2 when the furnace is shut down.

The electrical control system, in accordance with my invention, includes electrical ignition means for the pilot burner 2 which is preferably of the type disclosed in detail in my patent and copending application Serial No. 276,475, filed

concurrently, and includes a jump spark gap 8 which bridges the flame space projecting from the pilot burner nozzle. In addition to the spark gap 8 for the pilot burner, the branch conduits 4 and 5 are provided with electrically operated valves 9 and 10 respectively, such as disclosed in my patent, which are opened when energized by the electrical control system.

The electrical system for controlling the burner operation in accordance with the present invention, includes a step-up transformer 11 having a primary winding 12 and a secondary winding 13, which supplies a secondary potential sufficient to bridge the jump spark gap 8 of pilot burner 2 during the normal operation of the furnace. Current for opening electrically operated valves 9 and 10 is dependent upon a pair of relays 14 and 15, which in turn are dependent upon the operating conditions of transformer 11 and is illustrated as a step-down transformer having its primary 17 directly connected with the high potential secondary 13 of transformer 11 and the circuit of its secondary 18 associated with said relays, as will be set forth.

Transformer 11 is adapted to be supplied with alternating current by a usual source of supply 19, from a switch 20, by conductor 21, to end 22 of primary winding 12, winding 12 of transformer 11, thence from end 23 of winding 12, by conductor 24, through operating solenoid 25 of relay 14, by conductor 26, to contact 27 of a double pole double throw switch 28, blade 29 of said switch, by conductor 30, back by switch 20, to source 19.

The secondary winding 13 of transformer 11 has one end of its winding grounded as indicated at 31 and its other end is connected by conductor 32 with gap 8 of pilot burner 2 through insulated connections therewith, as disclosed in my other cases referred to herein. When transformer 11 is energized as just described, the potential of its secondary is sufficient to jump the gap 8 in the event there is a flame issuing from the jet of the pilot burner but this potential is insufficient to break the gap across air, in the absence of the pilot flame, and the transformer draws only a small current not enough to energize the operating solenoid 25 of relay 14; the circuit contacts of this relay thus remain open, and other operating equipment remains in off position. Under these conditions, and whenever there is a failure of the pilot burner, the equipment being connected through switch 20 with a supply of power, a signal device 33, such as a bell, lamp, or the like is operated from said

source. The circuit thereby provided for this signal appliance 33, is from switch 20, conductors 21, 34, through signal device 33, thence conductor 35, upper contacts 36 of relay 15 which are closed by the movable contactor 37 thereof, and back to the other side of the source of power by conductors 38 and 30 to switch 20.

It is to be noted that the double pole double throw switch 28 is normally maintained in the position shown and is manually operable to its other position indicated in dotted lines, a spring 39' immediately returning it to normal position upon release of such manual operation.

To supply gas to and ignite the gas issuing from pilot burner 2, valve 10 must be energized to open and the potential supplied to gap 8 must be increased sufficiently to jump the air or un-ignited fuel space in the gap. To increase this potential, transformer 11 has its primary winding 12 provided with a tap 39 so that when the 15 source of power is connected with the primary with the appropriate lesser number of turns, the secondary potential will be increased the required amount. In order to do this, the switch 28 is manually moved to the dotted line position until the pilot burner has been ignited. By this operation the current is supplied from switch 20 by conductor 21, to end 22, winding 12 through 20 to tap 39, thence by conductor 40, contact 41 of switch 28, blade 29 thereof, and conductor 30, 30 back through switch 20 to the other side of the source, and at the same time a circuit from switch 20 is completed by conductors 21 and 42 through electrically operated valve 10, and back by conductor 43, blade 44 of switch 28, contact 45 thereof, and conductors 38 and 30, back to switch 20 and the other side of the source. In this way the fuel passage is opened to the pilot burner 2 and the ignition thereof is effected, 40 but electrically operated valve 9 remains closed since relays 14 and 15 are still open.

Upon ignition of the gas from the pilot burner, switch 28 is released so as to return to its normal position; the return of the switch is so quick as not to interfere with the flow of gas to this 45 burner by momentary closure of valve 10 which immediately opens upon closure of the switch 28 in its normal position under influence of spring 39. With the switch 28 in its normal position again the entire winding 12 of transformer 11 is connected with the source of current as previously set forth. The potential of secondary winding 13 is reduced but is sufficient to bridge the gap through the flame and thereby the primary winding 12 draws an increased amount of 55 current, sufficient through solenoid 25 of relay 14 to effect a closing of its circuit contacts.

Closing of the circuit contacts of relay 14 closes the circuit from secondary winding 18 of transformer 16, by conductor 46, closed circuit 60 contacts of relay 14, conductor 47, through solenoid 48 of relay 15, back by conductor 49 to the other end of winding 18. This energizes relay 15 drawing its movable contactor 37 to close the lower contacts 50 thereof. The circuits to both 65 electrically operated valves 10 and 9 are thus closed, namely: from the source at switch 20, conductors 21 and 42 to valves 10 and 9, thence from valve 10, through conductor 43, blade 44 of switch 28, contact 51 thereof, to conductor 52, and from valve 9 by conductor 53 directly to conductor 52, thence for both valve operating windings through lower contacts 50 closed by contactor 37, and conductors 38 and 30, to switch 70 20, to the other side of the source. Energizing

valve 10 maintains the proper supply of gas to pilot burner 2 and the energizing of valve 9 supplies gas to main burner 1 subject to its control by the usual operation of valve 6. As a means 5 for fixing the potential relationship of the secondary winding 18 of transformer 16, a conductor 54 may be connected from one end of this secondary 18 to one end of the primary 12 of transformer 11 as indicated at 22 which may 10 preferably be connected with the grounded side of the source of electric current supply.

After ignition of the pilot burner flame and return of switch 28 to its normal position as just set forth, the control system is operating under 15 normal conditions. The valves 9 and 10 will remain in their open positions until the flame of the pilot burner is removed from the gap 8. Should this occur, the current in relay 14 will be reduced to such a point that it will drop out, thus opening relay 15 and thereby causing both 20 gas valves to close, and effect the actuation of the signal device 33. Another condition, if it should occur, will also cause the gas valves to close; if a short circuit of the secondary 13 of transformer 11, or of the gap 8, or of the conductors leading to the gap, should occur it would 25 result in the short circuiting of the primary 17 of transformer 16, thereby reducing its secondary voltage to zero or to such an extent that relay 15 would drop out, resulting in the closing of the fuel valves.

This last condition is important as a safety measure in the operation of the system since without such a feature an accumulation of soot 30 in the pilot burner or a "ground" of the high tension cable supplying the burner would cause the relay to remain closed and fuel valves open even if the pilot were not lighted.

Having described a highly satisfactory arrangement of my invention, I do not wish to limit myself to any of the specific arrangement details for the purpose of giving an example or illustration of employment of the invention for it will be obvious that wide departure from the above may be made without departing from the spirit and scope of my invention, which is as set forth in the following claims.

I claim:

1. A safety control and ignition system for fuel burners, including a burner with a spark gap bridging the flame space projecting from a fuel jet of the burner, a transformer having a primary winding, and a high potential secondary connected with said spark gap of the burner, a source of alternating current supply, means normally connecting said source of current supply with said primary winding of the transformer so as to produce a potential in the secondary winding sufficient only to produce a passage of sparks across the gap when a flame is present therein but operable to connect a lesser number of turns of the transformer primary winding with the source of current supply to increase the secondary potential for fuel ignition, means dependent upon the current consumption of the transformer for controlling the supply of fuel to the burner, and means for shutting off the supply of fuel to the burner in the event of excessive current flow from the secondary winding of the transformer.

2. A safety control and ignition system for fuel burners, including a burner with a spark gap bridging the flame space projecting from a fuel jet of the burner, a transformer having a primary winding, and a high potential secondary

connected with said spark gap of the burner, a source of alternating current supply, means normally connecting said source of current supply with said primary winding of the transformer so as to produce a potential in the secondary winding sufficient only to produce a passage of sparks across the gap when a flame is present therein but operable to connect a lesser number of turns of the transformer primary winding with the source of current supply to increase the secondary potential for fuel ignition, means dependent upon the current consumption of the transformer for controlling the supply of fuel to the burner, means for shutting off the supply of fuel to the burner in the event of excessive current flow from the secondary winding of the transformer, said means including a second transformer excited from the secondary winding of said first transformer, and a relay operable by said second transformer only during the normal operation of the first transformer in passing sparks through a flame in the spark gap.

3. A safety control and ignition system for fuel burners, including a burner with a spark gap bridging the flame space projecting from a fuel jet of the burner, a transformer having a primary winding, and a high potential secondary connected with said spark gap of the burner, a source of alternating current supply, means for connecting said source of current supply with said primary winding of the transformer so as to produce a potential in the secondary winding sufficient to produce a passage of sparks across the gap for ignition purposes or a lower potential only sufficient to produce a passage of sparks across the gap when a flame is present therein, a relay connected with the primary winding of the transformer and dependent for its operation upon the current passing therethrough when the secondary winding is producing a potential which produces a passage of sparks through a flame from the burner, a second relay dependent upon the potential supplied to the spark gap and upon the operation of said first relay, electrically operated valves for the fuel burners, and means for connecting said electrically operated valves with the source of current supply dependent upon the operation of said two relays for actuating the valves to their open position.

4. A safety control and ignition system for fuel burners, including a burner with a spark gap bridging the flame space projecting from a fuel jet of the burner, a transformer having a primary winding, and a high potential secondary connected with said spark gap of the burner, a source of alternating current supply, means for connecting said source of current supply with said primary winding of the transformer so as to produce a potential in the secondary winding sufficient to produce a passage of sparks across the gap for ignition pur-

poses or a lower potential only sufficient to produce a passage of sparks across the gap when a flame is present therein, a relay connected with the primary winding of the transformer and dependent for its operation upon the current passing therethrough when the secondary winding is producing a potential which produces a passage of sparks through a flame from the burner, a second relay dependent upon the potential supplied to the spark gap and upon the operation of said first relay, electrically operated valves for the fuel burners, means for connecting said electrically operated valves with the source of current supply dependent upon the operation of said two relays for actuating the valves to their open position, and means for shifting the connections of the source of current supply with the primary winding of said transformer for effecting ignition of fuel from the burner and simultaneously connecting the electrically operated valve for the burner having the spark gap with the source of current supply independent of said relays until the fuel has been ignited.

5. A safety control and ignition system for fuel burners, including a burner with a spark gap bridging the flame space projecting from a fuel jet of the burner, a transformer having a primary winding, and a high potential secondary connected with said spark gap of the burner, a source of alternating current supply, means for connecting said source of current supply with said primary winding of the transformer so as to produce a potential in the secondary winding sufficient to produce a passage of sparks across the gap for ignition purposes or a lower potential only sufficient to produce a passage of sparks across the gap when a flame is present therein, a relay connected with the primary winding of the transformer and dependent for its operation upon the current passing therethrough when the secondary winding is producing a potential which produces a passage of sparks through a flame from the burner, a second relay dependent upon the potential supplied to the spark gap and upon the operation of said first relay, electrically operated valves for the fuel burners, means for connecting said electrically operated valves with the source of current supply dependent upon the operation of said two relays for actuating the valves to their open position, and means for shifting the connections of the source of current supply with the primary winding of said transformer for effecting ignition of fuel from the burner and simultaneously connecting the electrically operated valve for the burner having the spark gap with the source of current supply independent of said relays until the fuel has been ignited, a signal device, and means for connecting said signal device with the source of current supply whenever either of said relays is deenergized.

JAMES K. CLARK.
